FURNACE GRATE STRUCTURE

Joseph S. Bennett, Merion, Pa., assignor to
American Engineering Company, Philadelphia,
Pa., a corporation of Pennsylvania

Application July 28, 1931, Serial No. 553,622

10 Claims. (Cl. 110—44)

This invention relates to improvements in furnace grate structures and, while applicable in principle to other types of grates and stokers, finds an application of particular value in the 5 extension grates of multiple-retort, underfeed stokers.

One object of my invention is to provide a grate structure of novel and generally improved design and construction.

10 Another object of the invention is to provide a novel form of grate construction, applicable to mechanical stokers, in which the fuel-supporting surface is composed of a plurality of relatively small readily replaceable elements.

15 A still further object is to provide a stoker extension or like grate wherein the passages for combustion air to the fuel-bed are substantially free from any tendency to clog from accumulation of siftings or from other causes.

20 Still another object of the invention is to provide a stoker extension or like grate wherein the passages for combustion air in any part of the grate may be readily modified to meet any special condition.

25 Another object is to provide a grate of the stated type wherein provision is made for free expansion of those portions of the grate exposed to the fuel.

Still another object is to provide a stoker extension or like grate including a plurality of 30 securely anchored, replaceable fuel-supporting elements wherein said elements are free to expand both laterally and in the longitudinal direction.

35 A further object of the invention is to provide a stoker extension or like grate wherein any part or all of said grate is renewable without affecting the other parts of the stoker structure.

Still another object of the invention is to provide 40 a mobile extension grate or equivalent stoker member comprising a suitably formed metallic framework and a plurality of elements removably mounted in said framework and forming the effective fuel-surface.

45 A further object of the invention is to provide in a stoker grate member of the stated character a novel form of detachable facing element including means for passing combustion air through the grate to the fuel-bed.

50 A further object of my invention is to provide a metallic framework which will so support non-metallic facing elements which are relatively weak in such a fashion as to utilize their resistance to heat without excessive mechanical breakage.

55 The invention further resides in novel means

for securing the facing elements or blocks in the supporting framework of the grate, and in various other structural details hereinafter set forth and illustrated in the attached drawings, in which:

Fig. 1 is a longitudinal section showing a part of the lower or overfeed section of a multiple retort underfeed stoker and one section of the extension grate in side elevation;

Fig. 2 is a rear elevation of the portion of the 10 stoker shown in Fig. 1;

Fig. 3 is a top plan view of one of the extension grate sections;

Fig. 4 is a side elevation and partial sectional view of the extension grate section shown in 15 Fig. 3;

Fig. 5 is a top plan view of the top cross bar of one of the extension grate sections;

Fig. 6 is a rear elevation of the said top bar;

Fig. 7 is a section on the line 7—7, Fig. 6; 20

Fig. 8 is a view in perspective of one of the lower cross bars of the extension grate sections;

Fig. 9 is a top plan view of the lower rear portion of one of the extension grate sections;

Fig. 10 is a section on the line 10—10, Fig. 9; 25

Fig. 11 is a view in perspective of one of the tie plates which unite the forward and rear parts of the individual extension grate sections;

Fig. 12 is a view in perspective of one of the facing blocks; and 30

Fig. 13 is a view in perspective of one of the lower terminal blocks of the extension grate.

With reference to Fig. 1 of the drawings, 1 is the dead plate positioned at the lower end of the inclined retorts of an underfeed stoker of a well known type, over which dead plate the fuel discharged from the retorts passes to an extension grate 2. This extension grate terminates at its lower end in an ash pocket 3, the forward wall of which is indicated at 4. In the present instance, the entire rear or overfeed portion of the stoker including the dead plate 1, the extension grate 2 and the lower grate 4, is carried at the lower end of a series of inclined beams, the upper edge of one of which is indicated at 5 and 45 is supported on a suitable underlying support structure. The extension grate 2 preferably is formed of a plurality of units extending transversely across the width of the stoker, portions of four of these units being illustrated in Fig. 50 2 and being respectively designated by the reference numeral 2. These units are mounted for individual movement in the stoker structure, being slidably supported in guide beams 6. A forward and rear reciprocation of the extension 55

grate units is effected by suitable actuating mechanism through the medium of a rod or rods 7 connecting to the forward or inner sides of the said units and extending forwardly of the stoker 5 below the dead plate 1. Reciprocation of the extension grate units results in a movement of the fuel and the fuel residue or ash into the ash pocket 3, the movement of the extension grate being in timed relation with the fuel feeding devices of the overfeed section of the stoker. 10

As illustrated in the drawings, each of the extension grate units comprises a forward section 11 and a rear or lower section 12. The forward section 11 comprises a pair of side plates 13, 13 which are united by a plurality of transverse bars 14 and 15, said plates and bars forming in effect an open frame. Each of the plates 13 is formed with forward and rear substantially vertical edges 16 and 17 and a horizontal bottom edge 18. The upper edge 19 of each of the plates inclines upwardly from the top of the rear edge 17 and terminates in a substantially horizontal top edge portion 21. The transverse bar 15 extends between the plates directly below the upper edge portion 21, and the bars 14 are secured in spaced relation to each other and to the upper bar 15 immediately below the inclined edge 19, thereby forming in effect an inclined series substantially parallel to said edge. 20

The top bar 15 is illustrated in detail in Figs. 4 to 7, inclusive. As therein illustrated, this bar comprises end flanges 22 which in assembly lie flat against the inner faces of the side plates 13 and which provide means for bolting the bars to the plates, the bolts being indicated in the assembly view of Fig. 4 by the reference numeral 23. The bar 15 further comprises a horizontal web 24 which extends transversely between the inner faces of the end flanges 22, which web in its mid section is formed with a substantially cylindrical boss 25 forming a socket for reception of the end of the actuating rod 1. The web 24 at its forward edge is flanged vertically, the said flange being indicated by the reference numeral 26, see Fig. 7, this flange serving for longitudinal reinforcement of the bar; and at its rear edge the web 24 has a similar flange 27 which at its upper edge is provided with a plurality of inwardly turned apertured lugs 28 functioning for a purpose hereinafter set forth. 30

One of the bars 14 is illustrated in Fig. 8. These bars are of a modified T-section, the flange 31 constituting one leg of said T assuming a vertical position, and the other leg 32 extending towards the forward side of the extension grate. At the ends, the bars 14 are provided with transverse flanges 33 which present flat surfaces for abutment with the inner faces of the plates 13 and which in the present instance are apertured for reception of bolts 34 by means of which the said bars are secured to the side plates. 40

The rear or lower section 12 consists in the present instance of an integral substantially triangular member including side plates 36 and a plurality of cross bars designated respectively in Fig. 9 by the reference numerals 37—38—39—41. These cross bars as shown in Fig. 10 differ from each other as to cross sectional form, but it will be noted that each of the bars 37—38—39 has an upstanding flange 42 and a substantially vertical rear face 43, these faces in the present instance being provided with a plurality of vertical ribs 44 for a purpose hereinafter set forth. The lower cross bar 41 is relatively flat, but is also provided 50 at its rearward edge with an upstanding flange

45. The forward edges of the side plates 36 of this lower section are adapted to abut the rear edges 17 of the side plates of the section 11, the two sections 11 and 12 being secured together through the medium of tie plates 46 which overlap the adjoining edges of the side plates and are secured against the inner surfaces of the plates by means in the present instance of bolts 47. It will be noted also that the rear edges 17 of the side plates of the section 11 are formed with a projecting flange 48, while complementary flanges 49 are provided on the forward edges of the side plates 36 of the section 12. These flanges form an overlapping joint between the side plates of the two sections. 15

In assembly, the various elements described above form a substantially rigid open framework of approximately triangular form with a plurality of transverse bars extending in an inclined series between the sides along the upper inclined edges 20 of the plates.

In conjunction with the frame described above, I provide a plurality of blocks which are adapted to be mounted detachably on the frame to form the effective fuel-supporting surface of the grate. 25 In the present instance, I provide two series of blocks, representative blocks of the two series being shown in Figs. 12 and 13 respectively. The blocks 51 shown in Fig. 12 consist of a substantially rectangular body portion having at the 30 front and on the under side a depending rectangular portion 52. At both sides of the member 52, the under side of the block is cut away to form inclined planes 53 which extend from the bottom surface of the block forwardly and upwardly and terminate slightly below the top front edge. With the block mounted in a substantially horizontal position, the inclination of the planes 53 corresponds with the inclination of the upper edge of the side plates of the extension grate 35 section. The block 51 is provided on the two sides and bottom surface and in the front and rear faces of the depending portion 52 with grooves 54, the grooves in the said side and bottom faces extending from the rear face of the 40 block to the inclined planes 53, and the grooves 55 in the front and rear faces of the depending portion 52 extending vertically the entire length of the faces which they occupy. 45

The blocks 56 shown in Fig. 13 are similar in 50 general form to the blocks 51, but differ therefrom in that they include at the rear under side a depending portion 57. These blocks like the blocks 51 include the inclined surfaces 58 corresponding to the surfaces 53 of the block 51, and intermediate these inclined faces a depending substantially rectangular portion 59. Intermediate the depending portions 57 and 59 is a transverse recess 61. These blocks like the block 51 are provided in their side faces with grooves 62 and 60 in the forward face of the depending portion 59 with grooves 63. 55

The blocks 56 are adapted to be mounted as illustrated in Fig. 4 upon the lower cross bars 41, the flange 45 of the cross bar entering the recess 65 61 of the blocks, and the forward face of the depending portion 59 abutting the vertical rear face of the cross bar 39. The blocks are placed side by side as shown in Fig. 3, there being in the present embodiment four of these blocks for 70 each grate section. The outer inclined face of the terminal blocks of the series rests upon the inclined upper edges of the side plates of the grate section.

The blocks 51 are mounted in similar series 75

upon the other cross bars of the frame exclusive of the top cross bar 15. As shown in Fig. 4, the rear end of each of these blocks rests upon the top of the underlying block, while the forward face of the depending section 52 abuts the vertical surface of one of the cross bars. The rear lower edge of the depending portion 52 lies behind and below the top of the upwardly extending flange of the next lower cross bar, so that these blocks are securely locked in position in the structure. Any of the blocks, however, may be withdrawn from the structure by tilting the rear end upwardly sufficiently to clear the depending portion 52 from the underlying cross bar and the forward upper edge of the next lower block. In order to prevent accidental displacement of the uppermost series of blocks, I provide a cap plate 65 which rests upon the upper edges of the side plates 13 and extends rearwardly over the said series of blocks. This cap plate is secured in position by bolts 66 which pass downwardly through the lugs 28 of the top cross bar 15.

It will be noted that the grooves in the faces of the blocks 51 and 56 together with the ribs 25 projecting from the rear faces of the lower group of cross bars provide air channels for passage of air from below the grate to the fuel-bed. These grooves also provide for free circulation of air around the blocks to air-cool the latter and 30 to prevent destruction thereof by heat. All of the grooves extending to the fuel-bed terminate in vertical surfaces of the blocks so that there is no tendency for the air passages to clog from accumulation of ash siftings therein, and the flow 35 of air around the blocks to the fuel-bed is maintained continuously at maximum efficiency. Also, the blocks being arranged in true vertical series, there are no pockets in which siftings may accumulate. Destruction of the blocks due to 40 burning is thus largely avoided and the efficiency of combustion in this part of the furnace is maintained at a maximum. By increasing or decreasing the depth of the air grooves in one or more of the blocks, the flow of air to any part of 45 the related portion of the fuel-bed may be varied to meet any special condition.

By forming the grate of a plurality of transversely arranged units, and by employing for the fuel-supporting portions of these units a plurality of facing blocks securely anchored yet sufficiently loosely assembled to permit substantially free expansion in all directions, the difficulties experienced in the prior types of grate due to 50 excessive expansion are eliminated. There is no binding from this cause between the units, nor between the blocks of the transverse and vertical series of the individual units, nor between the blocks and their supporting frames. Where replacements are required, therefore, the individual 55 blocks are readily withdrawn and new blocks inserted.

The construction also provides for utilizing in those portions of the grate where excessive burning is likely to occur, materials especially suited 60 to withstand the high temperature conditions. The lower transverse series of blocks, for example, might be formed of silicon carbide or other high refractory material; or the entire group of blocks might be so constituted.

70 The extension grate as described above has exceptional strength and durability. The pressures exerted by the fuel-bed as the grate sections are advanced are in a substantially straight line from the rear to the forward faces of the blocks 75 51 and 56. The forward faces of the blocks,

however, are in direct abutting relation to the vertical rear faces of the cross bars, and the latter 5 amply reinforce the blocks against all normal strains. The blocks 51 and 56 may be formed of any suitable refractory or heat-resisting material, such for example as cast iron, or silicon carbide, capable of withstanding the compressive forces normally applied thereto. The removable feature of the facing blocks is of great importance by reason of the fact that if one or more of these 10 blocks is destroyed by excessive overheating or from other cause, they may be readily and rapidly replaced without dismounting any part of the grate as a whole. The framework of the grate being nowhere in direct contact with the fuel is 15 not subject to destructive heat action. These factors are of particular value in conjunction with the extension grates of underfeed stokers of the type set forth, since considerable difficulty has been experienced in maintaining these grates in 20 continuous operation. These grates constituting a major part of the overfeed section of the stoker, and being in direct contact with the incandescent fuel, are subject to burning particularly where, as is becoming general practice, preheated combustion air is employed. While the construction is of particular significance in connection with stoker extension grates, as set forth above, it may find useful application in principle to other furnace grate structures; and there are to be no 25 implied limitations beyond those specifically imposed by the terms of the claims.

I claim:

1. A stoker grate structure comprising a frame including a plurality of transverse bars arranged 35 in an inclined series, and a plurality of facing elements mounted on said bars and forming the effective fuel-supporting surface of the grate, each of said elements having a face abutting an opposed face of one of the bars and having also 40 a depending portion normally disposed in substantially abutting relation with the next lower bar of the series whereby accidental displacement of the elements from the frame is prevented.

2. A furnace grate structure comprising a plurality of transverse bars arranged in an inclined series, a series of facing elements supported by and interlocked with the lower of said bars, each of said elements having a forward face abutting an opposed face of the next higher bar, and a 50 second series of facing elements, each of said last mentioned elements having a rear projecting portion seated on the top of the elements first named and having a forward face abutting one of the cross bars of said inclined series, each of 55 the last-named elements having a depending portion disposed in substantially abutting relation with the underlying cross bar to prevent accidental displacement of the elements from the grate structure.

3. A furnace grate structure comprising a plurality of transverse bars arranged in an inclined series, a series of facing elements mounted on and detachably secured to the lowermost of said bars, and a plurality of series of elements 65 mounted in superimposed relation upon the elements first named, each of the elements of the said series having a depending portion lying between adjacent transverse bars, and each of the bars of the series constituting a backing for one 70 of the series of said elements.

4. A stoker extension grate unit comprising a pair of side plates and an inclined series of cross bars connecting said plates, a plurality of series 75 of facing elements supported on said bars, each

of said elements having a forward surface in abutment with one of the bars and a rearward surface disposed in substantially abutting relation with an underlying bar, the latter surface being disengageable from the said underlying bar by elevation of the rear end of said element to permit removal of the element from the structure.

5. An extension grate for mechanical stokers comprising vertical side plates, and a plurality of bars extending transversely between and uniting said plates, said bars being arranged in an inclined series, a plurality of blocks of refractory material supported in horizontal rows and extending between the adjacent bars, each of said blocks 10 having a forward surface abutting one of said bars, and a depending portion extending below the top of the next lower bar of said series whereby said blocks are detachably retained in the framework, and each of said blocks having a 15 rearwardly extending portion overlying and supported on the top of a block of the immediately underlying row, said rearward extensions producing an effective fuel-supporting surface of stepped formation.

20. 6. An extension grate for mechanical stokers comprising an inclined series of spaced horizontal bars, a plurality of blocks of refractory material mounted upon said bars in superimposed horizontal rows, each of said blocks having a forward surface abutting one of said bars, and a depending portion extending below the top of the next lower bar, and each of said blocks also 25 having a part extending rearwardly from said depending portion and finding a support upon the upper surface of the blocks of the immediately underlying row, said blocks forming an effective fuel-supporting surface.

30. 7. A furnace grate structure comprising a plurality of series of elements arranged in superimposed series and constituting the effective fuel supporting surface of the grate, each of said elements having a substantially vertical forward face, and a depending portion, cross bars arranged in inclined series for supporting said elements and against which the vertical forward 35 faces of said elements abut, and said depending portions extending between and in substantially abutting relation with adjacent cross bars whereby accidental movement thereof is prevented.

40. 8. A grate block adapted for assembly with similar blocks in side by side relation upon a framework of a reciprocable extension grate, said block comprising a substantially rectangular body portion, having a substantially vertical fuel feeding surface, substantially horizontal top and bottom surfaces, and substantially vertical side surfaces, a substantially rectangular projection

depending from said body portion having substantially vertical side, front and rear faces, the front face of said projection being substantially flush with the front edge of said body portion, an inclined supporting surface on said body portion extending laterally from each side face of said projection, substantially longitudinal ribs on the side and bottom surfaces of said body portion and substantially vertical ribs on the front face of said projection.

5. 9. A grate block adapted for assembly with similar blocks in side by side relation upon a framework of a reciprocable extension grate, said block comprising a substantially rectangular body portion having a substantially vertical fuel feeding surface, a substantially horizontal fuel supporting surface, and substantially vertical side surfaces, a substantially rectangular projection depending from said body portion and extending substantially from the front edge 10 thereof to a point intermediate said front edge and said fuel feeding surface, said projection having substantially vertical side, front and rear faces, a second projection depending from said body portion in spaced relation with said first 15 mentioned projection forming a recess therebetween, a downwardly inclined supporting surface disposed on each side of said first mentioned projection, substantially longitudinal ribs on the side surfaces of said body portion and substantially vertical ribs on the front face of said first 20 mentioned projection.

30. 10. An extension grate for stokers comprising in combination, a plurality of transverse rows of 35 refractory blocks arranged in superimposed stepped relation, and a framework for supporting said blocks, said framework including spaced side members, and supporting means disposed between said side members, said supporting means including upper, lower, and intermediate transverse members, the lowermost of said transverse members comprising a substantially flat portion 40 and a vertical flange extending upwardly therefrom, means provided on each of the lowermost rows of blocks adapted in assembly to interlock with said flange whereby said blocks are anchored in position, interlocking means provided on the other of said transverse rows of blocks and the intermediate of said transverse members, retaining means detachably secured to the 45 upper of said transverse members and overlying the uppermost of said rows of blocks for preventing vertical displacement of said blocks, and means disposed between adjacent blocks defining 50 passages for draft air.

55. JOSEPH S. BENNETT.
